UNITED STATES PATENT OFFICE.

SAMUEL M. WILSON, OF DAVENPORT, IOWA.

Mechanical Movements for Washing-Machines.

3,126,166.

Specification of Letters Patent. Numbered Sept. 23, 1913.

Application filed June 26, 1912. Serial No. 474,761.

To all whom it may concern:

Be it known that E. BAXTER T. WILSON, a citizen of the United States, residing at Davenport, in the county of Scott and State of Iowa, have invented new and useful improvements in Mechanical Movements for Washing-Machines, of which the following is a full, clear, and exact description:

My invention relates to mechanical movements particularly adapted to laundry washing machines and wringers, and more particularly to the type of domestic machines possessing a horizontally disposed rotary reciprocating cylinder.

The principal object of my invention is to provide simple and effective mechanism that will revolve the cylinder one or more revolutions in one direction and then a corresponding distance in the opposite direction.

Another object of said invention is to enable the operator to release the driving mechanism from the cylinder by means that may be manipulated by him either when standing in front or in the rear of the machine, and still another object is to enable the operator to transmit power to the wringer mechanism so as to revolve the same in which ever direction it is desired to have the rollers turn, from a position either in front or in the rear of the machine, and yet another object is to guard the actuating mechanism of the cylinder where the parts employed are adapted to be disengaged.

These and other objects I accomplish by the means and in the manner hereinafter fully described and as more particularly pointed out in the claims, reference being had to the accompanying drawings forming a part of this specification, in which—

Figure 1 is an end elevation of my improved mechanical movement, showing the same applied to the tub and frame of a cylinder washing machine. Fig. 2 is a side elevation of the end portion of the machine to which my improvements are applied. Fig. 3 is an enlarged fragmentary end elevation. Fig. 4 is a vertical longitudinal section taken on line 4—4. Fig. 5, Fig. 6 is a horizontal section thereof taken on line 5—5, Fig. 3. Fig. 6 is a horizontal section taken on line 6—6, Fig. 1 of the end of the machine to which my improvements are applied. Fig. 7 is a horizontal section of said end portion of the machine taken on line 7—7, Fig. 1. Fig. 8 is an enlarged detail view showing the wringer driving gears in one position in full lines, and in a reversing position in dotted lines. Fig. 9 is an enlarged detail view of one of the elements used in shifting the wringer driving gears. Fig. 10 is an enlarged detail view of a modified arrangement of the gearing employed in my improved mechanism.

The supporting frame-work of my improved washing machine is so constructed as to surround the cylindrical casing C within which the horizontally disposed rotary reciprocating cylinder A is inclosed, and so as to support the actuating mechanism of said cylinder A. This is situated at one end of the machine. Suffice it to say that this framework includes curved posts or legs B' that are preferably inclosed on suitable casters to enable the machine to be rolled with ease, and with suitable longitudinal rails B² connecting said legs near their lower ends, and suitable cross-bars connecting said rails near their ends and so constructed as to provide a platform upon which at one end of the machine the cylinder and gearing transmitting the motion thereto to the actuating mechanism of the cylinder are mounted. This supporting frame of the machine also includes a rectangular frame secured to the upper end of the legs to which the casing C is immediately attached, and the end pieces of this rectangular frame at one end of the machine is connected with a cross-bar B³ by a suitable standard B.

Cylinder A is provided at the ends with suitable journals a, and these journals may be bearings a that are mounted upon and made integral with standards B. At the end of the machine at which the actuating mechanism of the cylinder is located, the journal a extends through its bearings and has a small pinion 13 mounted thereon, and this pinion is engaged by a vertical reciprocating rock 14 that is moved up and down by means of a pitman 17, the upper end of which is pivotally connected to the rock at its lower end. The lower end of the pitman 17 is journaled upon a crank-pin 18 secured to and projecting from a comparatively large gear 16, and this gear 16 is actuated by a small pinion 8 mounted upon the adjacent end of and revolving with a suitable spindle 9. This spindle is journaled in bearings mounted upon the platform or the cross-bar B³, and its end opposite pinion 8 has a large gear 5 secured thereto which is

96

97

Cylinder A is provided at the ends with suitable journals a, and these journals may be bearings a that are mounted upon and made integral with standards B. At the end of the machine at which the actuating mechanism of the cylinder is located, the journal a extends through its bearings and has a small pinion 13 mounted thereon, and this pinion is engaged by a vertical reciprocating rock 14 that is moved up and down by means of a pitman 17, the upper end of which is pivotally connected to the rock at its lower end. The lower end of the pitman 17 is journaled upon a crank-pin 18 secured to and projecting from a comparatively large gear 16, and this gear 16 is actuated by a small pinion 8 mounted upon the adjacent end of and revolving with a suitable spindle 9. This spindle is journaled in bearings mounted upon the platform or the cross-bar B³, and its end opposite pinion 8 has a large gear 5 secured thereto which is

engaged and actuated by a pinion 5 mounted upon the idle-shaft, which latter has a concaved pulley 2 thereon, that is driven through the medium of a belt 3 by motor 1.

5 The rack 14 is inclosed within, and its reciprocations are guided by the vertically elongated channel of a casing 12, and the edges of the channel of this casing 12 are placed against the flat rocking-frame 13 and secured thereto by screws or other means fastening the outwardly extending flange α of one of its edges to said frame. The lower end of this frame 13 is pivotally mounted upon a stud 11 secured in and projecting from the lower end of standard B. Where the rack 14 engages the pinion 15 on the end of the journal of the cylinder, casing 12 is built laterally so as to provide a housing 16 for said pinion, and the horizontal axis of this housing is elongated so as to enable the rocking frame 13 to be moved in a direction away from and permit the pinion to disengage from the rack without uncovering said pinion.

15 In order to rock frame 13 so as to carry the rack either into or out of engagement with pinion 15, I provide it, opposite the housing 16, with a lug to which one end of link 22 is pivotally connected. The other end of this link is pivotally connected to the adjacent end of a lever 20 (of the first class), which latter is fulcrumed to a bracket 21 projecting from the adjacent edge of standard B. This lever 20 extends 20 beyond its fulcrum to a point adjacent the legs B' of the supporting-frame and is provided with a suitable outwardly projecting handle on its end with which to manipulate it. When this lever 20 is in a horizontal position, the casing 13 will be moved so as to throw the rack 14 into engagement with the pinion 15, and when it is depressed, as shown in dotted lines in Fig. 3, it will, through the medium of the link 22, draw the 25 rocking-frame and casing away from the pinion and disengage the rack therefrom.

In order to move the rocking-frame from the rear of the machine so as to carry the rack into and out of engagement with pinion 15, I have provided a lever 19 which is fulcrumed on a pivotal stud 12^b, which latter projects from the standard at a suitable point above the housing 16 in substantially the same vertical plane as the journals α of the cylinder. The longer arm of this lever 19 extends to and, preferably, terminates adjacent the rear leg of the frame-work of the machine where it is provided with a suitable handle with which to manipulate it. The 30 forward shorter branch of this lever 19 extends back of the rocking-frame to a point in the same vertical plane as the pivotal connection between the rear end of lever 20 and link 22, at which point it is connected by a 35 pendent link 23 to the pivotal member unit-

ing link 22 and lever 20. When the rack is in engagement with pinion 15, this lever 19 will always be in a horizontal position. When it is desired to move the rack away from said pinion, the rear end of said lever 19 is depressed, and this will raise the pivotal connection between the lever 20 and the link 22 and rock frame 13 so as to disengage said rack and pinion. In order to accommodate the extended end of the stud 12^b, I 70 have extended the web of the flanged edge of the channeled casing 12 just above the housing 16, substantially as shown in Figs. 1 and 3, and provided the same with a transversely elongated opening through which 75 said stud 12^b extends. This enlargement of the web of the flanged edge of casing 12 may be dispensed with, if desired, but I prefer to make it as shown in the drawings, because 80 said stud 12^b serves to limit the rocking 85 movement of the rocking-frame, and to insure a more perfect engagement between the teeth of the rack and the teeth of the pinion 15.

Washing machines of the character to 90 which my improvements are applied require the use of wringer mechanism in connection therewith and are not considered complete without the same. For this reason, it is necessary to provide such wringer mechanism and means for actuating the same so that the rollers thereof can be moved either in one direction or the other, or can be thrown out of engagement with the actuating mechanism of the machine entirely, accordingly as desired. In order to accomplish this result, I mount upon a horizontally disposed shaft 24, substantially parallel with the shaft of pulley 2, a small pinion 25 on the outer extended end of said 95 shaft a beveled or miter gear 26 that meshes with a beveled gear 27 that is at substantially right angles thereto. This miter gear 27 is fast on the lower end of a vertically disposed drive-shaft 28 for actuating the 100 wringer 29 mounted on the upper edge of the end piece of frame C'. In order to accomplish this the upper end of shaft 28 is provided with a miter gear 30, and the latter meshes with a miter gear 31, mounted on the extended end of the shaft of the drive-roller 32 of the wringer 29. Gears 30 and 31 are, preferably, surrounded and protected by a hemi-spherical shell or casing 33 having bearings 34 and 35 for both 105 shafts 32 and 28, as shown. Gears 27 and 26 at the lower end of shaft 28 are likewise surrounded and guarded by a hemi-spherical shell or casing 36, substantially as shown.

Between gear 25 and beveled pinion 26, 110 shaft 24 has a substantially triangular shaped bracket 37 pivoted thereon which is provided with two inwardly projecting studs 38 and 39 on which suitable gears 40 and 41 are mounted that mesh with each other. 115

When pivotal bracket 37 is moved downward sufficiently, gear 41 will mesh with a drive-pinion 6 mounted on spindle 7 between gears 9 and 8, and through the medium of gear 40 transmits motion to the pinion 25. When this bracket is raised sufficiently, gear 40 will come into mesh with drive gear 8 and will directly drive the pinion 25 in a reverse direction. In order to facilitate the changing of these gears and reverse the motion of the wringer mechanism, I provide a vertically disposed rod 42 which at its lower end is pivotally connected to bracket 37, and at its upper end is pivotally connected to the outer end of an arm 43 secured to a horizontally disposed rock shaft 44. This rock shaft is mounted in bearings 45 secured to and projecting from the ends of frame 3, and where said shaft extends beyond these bearings, it is provided with suitable vertically disposed handles or levers 46, the turning of which in one direction or the other rocks shaft 44, so as to raise or lower rod 42 and swing bracket 37 and cause gear 40 or gear 41 to engage gear 8. When at the limit of its raised or lowered position, bracket 43, to the outer end of which rod 42 is pivoted, will be on a "dead center", as shown in dotted lines in Fig. 9 of the drawings, and when said bracket is in a horizontal position, as shown in full lines in said figures, the gears will be disengaged.

Fig. 10 of the drawings shows a slightly modified arrangement of the gearing employed to reverse the wringer, in which the shifting of a single gear is used instead of two gears. This modification comprises a pulley 50 corresponding to pulley 2 in the preferred form, and gears 51 and 52 corresponding, respectively, to gears 6 and 10 in the preferred form. A pinion 53 is mounted on the end of the pulley-shaft and pinions 54 and 55 are secured to the outer end of the spindle 56. Pinion 53 derives its motion from said pulley-shaft and drives the large gear 51 mounted on one end of spindle 55, which latter, through the medium of pinion 54 on its opposite end, transmits motion to said large gear 52. Pinion 55 is, preferably, in mesh with and drives a pair of idle pinions 58 and 59 that are mounted upon suitable spindles secured to and projecting laterally from the adjacent portion of the platform or cross-bar 60 of the supporting frame of the machine. Pinions 58 and 59 are arranged with their axes in substantially the same vertical plane, while the axis of pinion 58 is slightly to one side thereof, located immediately above and with its axis in substantially the same vertical plane with pinion 58 is a supplemental pinion 61, that meshes with and derives its motion from pinion 59. All the pinions just mentioned (i.e., 55, 53, 58, 59 and 61) are of substantially

the same diameter and pitch and are so arranged that their axes substantially form the corners of an imaginary hexagonal figure.

Mounted on the outer end of a longitudinally disposed shaft 62 is a beveled pinion (not shown) through the medium of which the wringer is driven, as in the preferred form, and adjacent thereto a pinion 63 is mounted on said shaft. Between gear 63 and said omitted beveled pinion, shaft 62 has a suitable elongated bracket 64 pivoted thereto which is provided with a laterally projecting stud 65 on which a shiftable gear 66 is mounted in mesh with pinion 63. When this bracket is moved upwardly or downwardly sufficiently, the gear 66 will be brought into mesh with either pinion 61 or pinion 58, according to the direction in which it moves, and through the medium of pinion 66 will drive the wringer mechanism either forward or reversed, as the case may be. Bracket 64 of this modification is moved by a rod 67, similar in construction and operation to rod 42 of the preferred form.

What I claim as new is:

1. A mechanical movement comprising a rotary reciprocable horizontally disposed element having journals one end of which is extended, a pinion mounted on said extended end, and a vertically reciprocable rack adapted to engage said pinion and also adapted to be tilted from a pivotal point adjacent to its lower end out of engagement with said pinion.

2. A mechanical movement comprising a rotary reciprocable horizontally disposed element, journals therefor, a pinion mounted on one of said journals, and a reciprocable rack adapted to mesh with said pinion and also adapted to be tilted laterally from a pivot below its lower end, out of engagement therewith.

3. A mechanical movement comprising a rotary reciprocable horizontally disposed element, journals therefor, a pinion mounted on one of said journals, a reciprocable rack adapted to mesh with said pinion, and a vertically disposed frame supporting and directing the movement of said rack and pivoted at its lower end and adapted to be tilted laterally to carry said rack out of engagement with said pinion.

4. A mechanical movement comprising a rotary reciprocable horizontally disposed element, journals therefor, a pinion secured upon one of said journals, a reciprocable rack adapted to mesh with said pinion, a frame supporting said rack, and a housing mounted upon said frame including said pinion and rack and directing the movement of the latter; said frame being adapted to be tilted laterally on a fixed pivot and to carry the rack out of engagement with said pinion.

- 4
5. A mechanical movement comprising a rotary reciprocable horizontally disposed element, journals therefor, a pinion secured upon one of said journals, a reciprocable 5 rack adapted to mesh with said pinion, a frame supporting said rack, and a combined casing and housing the former consisting of a longitudinal channel for confining and directing the movements of said 10 rack, and the latter consisting of a substantially elliptical shaped shell inclosing the pinion and having its major axis transverse to said rack; said frame adapted to be moved laterally and to carry said rack out of engagement with said pinion.
6. A mechanical movement comprising a rotary reciprocable horizontally disposed element, journals therefor, a pinion mounted on one of said journals, a reciprocable 20 rack adapted to mesh with said pinion, a frame supporting and directing the movement of said rack and tiltable laterally from a fixed pivot to carry said rack out of engagement with said pinion, and means 25 for imparting said movement to said frame.
7. A mechanical movement comprising a rotary reciprocable horizontally disposed element, journals therefor, a pinion mounted on one of said journals, a reciprocable 30 rack adapted to mesh with said pinion, a frame supporting and directing the movement of said rack and tiltable laterally from a fixed pivot to carry said rack out of engagement with said pinion, and means extending laterally in opposite directions from 35 said frame and coacting therewith to move the same laterally.
8. A mechanical movement comprising a rotary reciprocable horizontally disposed element, journals therefor, a pinion mounted on one of said journals, a reciprocable 40 rack adapted to mesh with said pinion, a frame supporting and directing the movement of said rack and tiltable laterally from a fixed pivot to carry said rack out of engagement with said pinion, a laterally disposed lever, and devices connecting the same 45 to said frame whereby said frame is moved laterally.
9. A mechanical movement comprising a rotary reciprocable horizontally disposed element, journals therefor, a pinion mounted on one of said journals, a reciprocable 50 rack adapted to mesh with said pinion, a frame supporting and directing the movement of said rack and tiltable laterally from a fixed pivot to carry said rack out of engagement with said pinion, a laterally disposed lever and a link connecting the same 55 to said frame to move the same laterally.
10. A mechanical movement comprising a rotary reciprocable horizontally disposed element, journals therefor, a pinion mounted on one of said journals, a reciprocable 60 rack adapted to mesh with said pinion, a frame supporting and directing the movement of said rack and tiltable laterally from a fixed pivot to carry said rack out of engagement with said pinion, levers extending laterally in opposite directions to the length of said frame, and devices common to both of said levers for imparting the motion thereof to said frame.
11. A mechanical movement comprising a rotary reciprocable horizontally disposed element, journals therefor, a pinion mounted on one of said journals, a reciprocable 70 rack adapted to mesh with said pinion, a frame supporting and directing the movement of said rack and tiltable laterally from a fixed pivot to carry said rack out of engagement with said pinion, levers extending laterally in opposite directions to the length of said frame, and a link for connecting the adjacent ends of said levers, and another link for connecting one of said levers to said frame.
12. A mechanical movement comprising a rotary reciprocable horizontally disposed element, journals therefor, a pinion secured upon one of said journals, a reciprocable 80 rack adapted to mesh with said pinion, a frame supporting said rack, a housing mounted upon said frame inclosing said pinion and rack and directing the movement of the latter, levers extending laterally in opposite directions to the length of said frame, and devices common to both of said levers for imparting the motion thereof to said frame and carry the rack laterally out of engagement with said pinion.
13. A mechanical movement comprising a rotary reciprocable horizontally disposed element, journals therefor, a pinion secured upon one of said journals, a reciprocable 90 rack adapted to mesh with said pinion, a frame supporting said rack, a housing mounted upon said frame inclosing said pinion and rack and directing the movement of the latter; said frame being adapted to be tilted laterally and to carry the rack out of engagement with said pinion, a laterally disposed lever, and a link that imparts the motion thereof to said frame.
14. A mechanical movement comprising a horizontally disposed rotary reciprocable cylinder, journals therefor, a pinion secured on one of said journals, a reciprocable rack adapted to be tilted laterally from a pivotal point adjacent its lower end out of engagement with said pinion, a revolute wheel or gear, and a pitman for imparting the motion of said gear to said rack.
15. A mechanical movement comprising a horizontally disposed rotary reciprocable cylinder, journals therefor, a pinion secured on one of said journals, a reciprocable rack adapted to be tilted laterally from a pivotal point adjacent its lower end out of engagement with said pinion, a revolute wheel 120

or gear, a pitman for imparting the motion of said gear to said rack, a lever extending laterally to said rack, and devices for imparting the motion of said lever to the same.

5 16. A mechanical movement comprising a horizontally disposed rotary reciprocable cylinder, journals therefor, a pinion secured on one of said journals, a reciprocable rack adapted to be tilted laterally from a pivotal 10 point adjacent to its lower end out of engagement with said pinion, a revoluble

wheel or gear, a pitman for imparting the motion of said gear to said rack, levers extending laterally in opposite directions to the length of said rack, and devices for imparting the motion thereof to said frame. 15

In witness whereof I have hereunto set my hand this 16 day of June, 1913.

SAMUEL T. WHITE.
